INDUCTIVE REGULATOR FOR COARSE AND FINE REGULATION

Rudolf Bauer, Berlin-Siemensstadt, Germany, assignor to Siemens & Halske, Aktiengesellschaft, Siemensstadt, near Berlin, Germany, a corporation of Germany

Application November 11, 1937, Serial No. 174,072
In Germany December 18, 1936

3 Claims. (Cl. 171—119)

The present invention relates to an inductive regulator for coarse and fine regulation.

If any finely graded variable alternating voltage is to be taken from an alternating-current supply circuit, devices are, as a rule, employed which possess a regulator for coarse regulation and one for fine regulation. The latter are preferably designed in the form of transformers with a secondary winding whose number of turns is variable, the number of the secondary turns being varied by moving a contact which varies the number of turns of the tapped winding. Such a device particularly employed for the above-mentioned purpose is shown in Fig. 1 in diagrammatic form.

In Figs. 2 to 5 are shown some embodiments of the invention of diagrammatic form, and Fig. 6 shows, partly in vertical section, a structural embodiment of my invention shown diagrammatically in Fig. 4.

Across the terminals 1 and 2 of the supply circuit is connected an inductive coarse regulator 3 which in the arrangement shown in Fig. 1 consists of a single winding arranged on an iron core not shown. To a portion of the winding 3 is connected a fine regulator 4 which may also consist of a single winding arranged on an iron core. Contacts 5 and 6 which may be moved along the windings 3 and 4 are connected to the output terminals 7 and 8 intended for a current consuming device 9. In this manner the corresponding variable parts of the coarse and fine regulator are connected in series so that also the winding of the fine regulator 4 must be rated for the maximum value of the current intensity of the current consuming device.

In the known devices the degree of regulation depends upon the number of turns of the winding of the fine regulator. However, since the cross-section of the wire must be dimensioned for the maximum value of the current flowing in the current consuming device, the dimensions of the fine regulator are the greater the more finely graded the regulation is to be. Furthermore, it is disadvantageous that the part of the coarse regulator, connected to the fine regulator, must supply the amount of energy necessary for the fine regulator.

In order that current may be taken from the windings two sliding contacts are provided traversed by the current flowing in the current consuming device, which contacts must be therefore suitably dimensioned and which represent variable contact resistances.

The above-mentioned drawbacks may be re-

moved according to the invention by providing means for inductively transferring the variable voltage tapped off from the fine regulator to the circuit including the current consuming device and connected to the coarse regulator. In this case the fine regulator may be connected to the primary or the secondary side of the coarse regulator or to a portion thereof. A particularly simple arrangement is obtained if the coarse regulator is employed at the same time as a fine regulator and is consequently provided with an additional sliding contact serving to tap off a voltage to be employed for the fine regulation.

In Figs. 2 to 4 the coarse regulator is designed as an inductive regulator with a primary winding 10 connected to the terminals 1 and 2 and a secondary winding 11 inductively coupled therewith. In the embodiment shown in Fig. 2 is provided an inductive fine regulator 12 which consists of a single winding and which is fixedly connected to a portion of the secondary winding 11 of the coarse regulator. However, the fine regulator might also be connected to the primary side of the coarse regulator. A contact 13 which extends to the output terminal 8 for the current consuming device 9 may be moved along the secondary winding 11. The other output terminal 7 is connected through the low-voltage winding 14 of an auxiliary transformer 15, 16 to the end point of the secondary winding 11 of the coarse regulator which is connected to the fine regulator 12.

The high-voltage winding 15 of this auxiliary transformer is at one end connected to a fixed point 16 of fine regulator winding 12 and at the other end to a contact 17 slidably arranged on winding 12. The point of connection is preferably arranged in the center of the winding 12.

When the terminals 1 and 2 are connected to an alternating-current supply circuit a corresponding alternating voltage is produced across the secondary winding 11. The voltage to be taken from the terminals 7, 8 may then be first regulated in a number of steps corresponding to the number of turns or contacts of the winding 11 by displacing the contact 13. If the contact 17 is in the center of the fine regulator winding 12, i. e., at the point 16, the voltage supplied to the transformer winding 15 is equal to zero. By displacing the contact 17 to the left or the right the resulting voltage is transmitted inductively in the one or the other sense to the low-voltage winding 14 in a number of steps corresponding to the number of turns of the fine regulator winding 12. In this case, the voltage transferred to

- the output circuit containing the current consuming device 9 is reduced in accordance with the transformation ratio of the transformer 14, 15. Depending upon the position of the contact 17 with respect to point 16 the voltage acts in an additive or subtractive manner so that the voltage across the terminals 1, 8 to be tapped off may be gradually increased or decreased by displacing the contact 17 of the fine regulator. In this case the arrangement of the tapping point 16 in the center of the fine regulator winding has the particular advantage that the transformer 14, 15 may be rated only for half the total voltage applied to the fine regulator.
- 18 The degree of regulation may be increased substantially at will by the arrangement according to the invention by selecting a correspondingly high transformation ratio for the transformer 14, 15.
- 20 In this manner the current intensity in the high-voltage winding 15 is accordingly reduced so that the fine regulator 12 may be wound with thin wire, i. e., with a correspondingly higher number of turns.
- 25 In the arrangement shown in Fig. 3 is provided a fine regulator having two separate windings 18, 19. The primary winding 18 is connected as in the embodiment shown in Fig. 2 to a portion of the secondary winding 11 of the coarse regulator and the center 20 of the secondary winding 19 is connected to that end of the secondary winding 11 of the coarse regulator to which also the primary winding 18 of the fine regulator is connected. Between the center 20 and the contact 21 slidably arranged on the secondary winding of the fine regulator a transformer 22 may be arranged in auto-transformer connection. A terminal 1 connected to a suitably chosen point 23 of the transformer 22 and a terminal 8 connected to the contact 13 slidably arranged on the secondary winding 11 of the coarse regulator serve to connect the current consuming device 9. In this case the tapping point 23 is preferably so placed that the current produced in the current consuming device 9 by the secondary voltage of the coarse regulator traverses the smaller portion of the transformer winding 22. In this manner similarly as in the arrangement shown in Fig. 2 a voltage is induced in the smaller portion of the winding 22, corresponding to the fine regulator voltage tapped off by the sliding contact 21. The degree of regulation may also be in this case chosen at will by correspondingly selecting the transformation ratio of the winding portions of the transformer 22.
- 50 In the embodiments of the invention shown in Figs. 4 and 5 a special fine regulator, such as 12 or 18, 19 in Figs. 2 or 3, is dispensed with and the coarse regulator is employed simultaneously as a fine regulator. To this end, two separate contacts 13 and 24 slidably arranged on the secondary winding 11 are provided in the embodiment according to Fig. 4.
- 55 In this case, the contact 13 connected to the output terminal 8 serves as in the above-described embodiments to effect a coarse regulation and the contact 24 to effect a fine regulation. Further, as in Fig. 2, an auxiliary transformer 14, 15 is employed, which has one terminal of its high voltage primary connected to slide 24 and the other terminal to a fixed point 25 of winding 11. Thus a voltage serving to effect a fine regulation is tapped off by the sliding contact 24 and supplied to the high-voltage winding 15 of the aux-

iliary transformer whose low-voltage winding 14, as in Fig. 2, is connected at one end to the end point of the secondary winding 11 and at the other end to the output terminal 1.

The arrangement shown in Fig. 5 differs from that in Fig. 4 merely by the use of an autotransformer consisting of a single winding 26 instead of the transformer 14, 15 in Fig. 4. In both cases, Fig. 4 as well as Fig. 5, as in the arrangement according to Fig. 2 a fine regulating voltage tapped off from the points 24, 25 of the regulator winding 11 and 26 respectively is transmitted additively or subtractively to the current consuming device circuit depending upon the position of the sliding contact 24.

With such an arrangement the degree of regulation is, of course, dependent upon the number of steps of the coarse regulator. If n is the number of turns of the regulating winding 11 and 26 respectively, the transformation ratio m of the transformer 14, 15 is chosen smaller than n . Each of the n coarse steps may be then subdivided again into m fine steps by displacing the fine regulating contact 24 along the regulator winding so as to result in a total of $m \cdot n$ fine steps.

Fig. 6 shows the construction of an inductive regulator according to the invention, the arrangement and the connection being the same as shown in Fig. 4. On a base 27 connected to a bearing plate 29 by means of columns 28 is secured a ring core 30 shown in cross-section and having a secondary winding 11 wound on top of a primary winding 18. In the plates 27 and 29 is mounted a shaft 31 and on the latter is journaled a hollow shaft 32. An arm 34 is secured to hollow shaft 32 but insulated therefrom by a disc 33. The arm 34 carries a stud 35 to which are resiliently secured rollers 13 in such a manner that they roll as brushes on the winding 11.

A contact brush 36 which is insulatedly secured to the plate 29 serves to connect the contact arm 34 to the terminal 8 not shown.

To the shaft 31 is insulatedly secured a second contact arm 37 at the end of which a roller 24 is resiliently mounted so that it is pressed against the same winding 11. A brush 38 insulatedly secured to the base plate 27 serves to receive current from the contact arm 37 to be conducted to winding 15 of Fig. 4.

To the hollow shaft 32 is secured a worm wheel 39 which is in engagement with a worm 40 so that the coarse regulating contact 13 may be adjusted by rotating the worm shaft. To adjust the fine regulating contact 24 the shaft 31 which is shown broken away in Fig. 6 may be rotated in any suitable manner not shown here. The remaining elements in Fig. 6 may be assumed as being provided and connected in the manner shown in Fig. 4.

What is claimed is:

1. An arrangement for supplying from an alternating current source to a consumer a voltage widely variable in fine steps, including a main variable voltage transformer connected to the current source and having an output winding 65 provided with a fixed end terminal and a step-wise variable terminal so as to derive variable output voltages from said winding in a given number of n steps, said consumer being connected to said fixed and to said variable terminal, 70 an auxiliary transformer having one terminal of its high voltage primary winding fixedly connected to the mid-point of said main transformer output winding and its other terminal variably connected to said output winding, said auxiliary 75

transformer having its low voltage secondary winding connected in circuit with said consumer, the transformation ratio m of said auxiliary transformer being not greater than the step number n of said main transformer.

- 5 2. An arrangement for supplying from an alternating current source to a consumer a voltage widely variable in fine steps, including a main variable voltage transformer having its primary 10 winding connected to said source and having a secondary winding provided with a fixed and a stepwise variable output terminal to derive variable voltages from said winding in a given number of n steps, said consumer being connected 15 to said fixed and to said variable terminal, and an auxiliary transformer having one terminal of its high voltage primary winding fixedly connected to the mid-point of said secondary main transformer winding and its other terminal 20 stepwise variably connected to said latter winding, and having its low voltage secondary winding connected in circuit with said consumer, the

transformation ratio m of said auxiliary transformer being not greater than the step number n of said main transformer.

3. An arrangement for supplying from an alternating current source to a consumer a voltage widely variable in fine steps, including an autotransformer having fixed outer terminals connected to the current source and an inner terminal variable in a given number of n steps, said consumer being connected to one of said fixed terminals and to said variable terminal for deriving a variable voltage therefrom, and an auxiliary transformer having one of its high voltage primary terminals fixedly connected to the winding mid-point of said autotransformer and its other 15 terminal variably connected to said winding, said auxiliary transformer having its low voltage secondary winding connected in circuit with said consumer, the transformation ratio m of said auxiliary transformer being not greater than the 20 step number n of said autotransformer.
